UNITED STATES PATENT OFFICE.

BAYARD E. TAYLOR, OF OAK PARK, ILLINOIS.

DOOR-LOCK.

1,246,348.

Specification of Letters Patent. Patented Nov. 13, 1917.

Application filed June 3, 1915. Serial No. 31,822.

To all whom it may concern:

Be it known that I, BAYARD E. TAYLOR, a citizen of the United States, and a resident of the city of Oak Park, in the county 5 of Cook and State of Illinois, have invented certain new and useful Improvements in Door-Locks; and I do hereby declare that the following is a full, clear, and exact description of the same, reference being

had to the accompanying drawings, and to the numerals of reference marked thereon, which form a part of this specification.

Considerable difficulty has been experienced in securing a lock adapted for auto- 15 mobile doors which will withstand the severe conditions to which the same is subjected without becoming loose and allowing the door to rattle. In the past locks have been used in conjunction with bumper 20 strips mounted upon the frame for the door against which the door is tightly thrust by the locking mechanism to prevent rattling of the door, but such strips soon become worn and fail in their purpose. Then, too, 25 in some instances, provision is made by supplementary locking mechanism on the door to lock the door in an open position, thus increasing the complication of parts and in many instances taking the form of un- 30 sightly devices which also, when not in use, hang loosely in a manner to easily rattle and also may become caught upon the garments of persons entering or leaving the car.

It is an object therefore of this invention 35 to construct a locking device for attachment to doors, windows, or the like, to positively lock the same in a closed position in a manner to prevent rattling thereof and also 40 capable of locking the door in any open position desired.

It is also an object of this invention to 45 construct a locking device embracing eccentrically operated means for positive engage- 45 ment with a flexible element to lock the door in closed position and with means oper- 50 ating under pressure to clamp said element to hold the door in any open position of adjustment.

It is also an object of this invention to 55 provide a door locking device embracing telescoping members having concealed therein a flexible steel strap element which has sliding engagement with a locking de- 55 vice whereby mechanisms within the lock- 55 ing device may engage said steel strap to

lock the door in an open or closed position, positively holding the same in a fixed position when so locked.

It is also an object of this invention to 60 construct a locking device embracing a plu- 60 rality of locking mechanisms independently operable to co-act with a unitary flexible element to retain a door in open or closed 65 position.

It is furthermore an important object of 65 this invention to construct a door locking device wherein spring actuated latching mechanisms are impelled into release position by eccentrically operating means acting 70 against spring tension, said latching means acting to engage through an aperture pro- 70 vided in a flexible element which is adjust- 75 ably connected to the door frame and hav- 75 ing slidable movement through the locking device whereby a yieldable but positive lock for the door is assured to hold the same closely in its frame when closed.

It is finally an object of this invention to 80 construct locking mechanisms acting yield- 80 ably to hold a door tightly closed in its frame or maintain the same in an open 85 adjusted position in a manner to prevent rattling of the door.

The invention (in a preferred form) is 85 illustrated in the drawings and hereinafter more fully described.

In the drawings:

Figure 1 is a fragmentary top plan view 90 of a door in a frame equipped with locking devices embodying the principles of my in- 90 vention.

Fig. 2 is a front face view of the locking 95 mechanism, with the door omitted.

Fig. 3 is an interior face view of the lock- 95 ing mechanism, with the rear cover plate of the casing omitted.

Fig. 4 is a fragmentary sectional view 100 similar to Fig. 1, and showing the door in partly open position.

Fig. 5 is a section taken on line 5—5 of 100 Fig. 2, with parts shown in elevation.

Fig. 6 is a similar view, showing the parts in another position of adjustment.

Fig. 7 is a detail section taken on line 105 7—7 of Fig. 2.

Fig. 8 is a rear elevation of the casing of the locking device.

Fig. 9 is a detail section taken on line 110 9—9 of Fig. 5.

Fig. 10 is a detail section taken on line 10—10 of Fig. 3.

Fig. 11 is a detail section taken on line 11-11 of Fig. 5.

Fig. 12 is an interior face view of the eccentric actuating means at one end of the 5 device.

Fig. 13 is a detail section taken on line 13-13 of Fig. 5.

Fig. 14 is a detail section taken on line 14-14 of Fig. 3.

10 As shown in the drawings:

The reference numeral 1, indicates as a whole a door or window mounted in a frame 2, by means of hinges 3, said door and frame forming a part of any structure whatsoever. Rigidly secured upon the 15 door 1, is a casing comprising a front plate 4, having side walls 5, integral therewith and reinforced by integral ribs 6, and with a rear cover plate 7, adapted to be secured 20 on said side walls 5, by means of screws 8, as shown in Fig. 8. Formed upon the outer surface of the wall 4, at one end thereof, is a boss 9, which is apertured and within which is journaled a short shaft 10, having 25 a toothed eccentric 11, integral therewith at one end, and a handle 12, for turning said shaft secured in any suitable manner, on the other end thereof.

Projecting perpendicularly from the inner surface of the eccentric 11, is a pin 13, and engaged thereon is one end of a connecting rod 14, the other end of which is engaged upon a pin 15, which projects upwardly from and is integral with or rigidly 35 secured upon a slidable plate 16, resting against the inner surface of the wall plate 4. The central portion of said plate 16, is cut away, as clearly shown in Figs. 3, 5, 6, and 10, and journaled between uprights 17, 40 provided at one end of said plate is a long arm 18, provided with a latch member 19, and having also formed integral therewith two short arms or cam teeth 20. Said arm 18, at its free end, is provided with lateral 45 extensions 21, which are recessed on their inner surfaces to receive seated therein coiled springs 22, as shown in Fig. 10, the other end of said springs seating in recessed portions of the plate 16, said springs acting 50 normally to impel said arm and latch 19, inwardly toward the plate 7. At the forward end of said plate 16, horizontal bosses 23, are formed on each side of the plate, and projecting outwardly therefrom in parallel 55 relation are rods 24, which slide through apertured brackets 25, provided on the inner surface of the wall of the casing.

Wound about each of said rods 24, are coiled compression springs 26, which, at 60 their ends, bear against the lugs 23, and brackets 25, respectively, to resist movement of the plate 16, toward the eccentric 11, when said plate is moved in such a direction, due to rotation of the eccentric. A tooth or 65 abutment 27, is provided on the interior of

the casing at one end thereof, and is adapted to be engaged by the toothed eccentric, as clearly shown in Fig. 12, and when the eccentric bears against said tooth 27, the pin 13, of the eccentric is past a dead center position. Consequently the pull on the eccentric exerted by the connecting rod 14, due to the compression springs 26, is resisted, and the device thus retained under spring tension in this position of adjustment with the plate 16, held toward the forward or eccentric end of the device. 70

Extending longitudinally slidably within the casing flat against the rear wall 7, thereof, is a flexible strap, preferably spring steel or the like, denoted by the reference numeral 28. Said strap is provided with a notch or aperture 29, therethrough, adapted to receive the latch 19, projected into engagement with one edge thereof in the manner shown in Fig. 5, to lock the device when the handle 12, is rotated to a horizontal position, and the cam into the position shown in Fig. 12. Integrally formed upon the rear end of the casing are eyes 30, adapted to receive engaged therebetween a tubular member 31, having a pin 32, extending through the end thereof affording a pivotal connection between said tubular member and said eye members. Said pin 32, is provided with a longitudinal slot therein through which said flexible strap element 28, extends, and the end of said strap is attached to a plug element 33, threaded for adjustment into another tubular member 34, 100 telescoped within said tubular member 31. 90

Tightly threaded into the other end of said tubular member 34, is another plug 35, which fits into a hinge bracket 36, and is adapted to receive a hinge pintle 37, inserted therethrough, said bracket being secured upon the frame 2, for the door or window upon which the device is used. As clearly shown in Fig. 9, the inner surface of the plate cover member 7, forming the inner wall of the casing, is grooved or recessed to receive the flexible strap 28, therein, so that proper disposition of said flexible element in all its positions within said casing is secured. As clearly shown in Fig. 8, the rear 110 cover plate 7, of the casing is provided with a pair of notches or slots 38, adapted to receive projected therethrough the arms 20, integral with the latch carrying arm 18, within the casing, to insure retraction of the 115 latch member 19, from the slot 29, of the flexible element when the slidable plate 16, is moved rearwardly within said casing. A slot 39, is also provided in said cover plate 7, to afford clearance for the latch 19, when 120 the same is projected through the slot provided therefor in the strap 28.

Another mechanism is provided for coaction with the flexible element 28, to effect locking of the door in any desired position, 130

and for this purpose an outwardly projecting boss 40, is formed at the rear end of the casing upon the front wall 4, and is apertured and internally threaded to receive a 5 screw bolt 41, engaged therein, provided with an actuating head 42, whereby rotation of said bolt serves to move the same inwardly or outwardly, as the case may be, in said boss. The inner end of said screw bolt 10 41, is provided with a circular head 43, engaging in a T-shaped slot in a clamping foot 44, which, when thrust inwardly due to rotation of the screw bolt, is forced firmly against the flexible strap element 28, serving 15 to clamp the same tightly against the rear wall 7, of the casing to hold the door in any position of adjustment. Said clamping foot 44, is prevented from longitudinal movement within the casing, which might result 20 in accidental disengagement thereof from the head 43, by lugs 45, formed on each side thereof and bearing against the integral inwardly directed end walls 46, formed within the casing, as shown in Fig. 3, the arrangement, 25 however, permitting movement of said clamping foot toward and away from the flexible strap element 28.

The operation is as follows:

The device with the handle 12, in the 30 horizontal position shown in Figs. 1, 2, and 5, is in locked position with the door closed, and in order to release the door to permit opening thereof, the handle 12, is rotated through an angle of ninety degrees and to 35 a perpendicular position, thereby rotating the eccentric and permitting the plate 16, connected to the eccentric through the connecting rod 14, to move rearwardly, due both to rotation of the eccentric and also 40 under the impulse of the compression springs 26. Such rearward movement of the plate 16, causes the latch member 19, to move out of contact with the edge of the slot 29, in the flexible element 28, and the 45 movement of the plate 16, continuing, also causes the arms 20, to contact the edge of the slots 38, in the cover plate 7, to cause the arm 18, and latch member 19, carried thereby, to swing downwardly within the casing, 50 permitting free movement of the flexible strap element 28. As the door or window upon which the device is connected is opened, said flexible strap element 28, slides through the casing, and the plug member 38, 55 to which it is securely connected, being mounted in the end of the tubular member 34, which is telescoped within the tubular member 31, said flexible strap element moves into or within said tubular member 31, as 60 the telescoping elements are extended, thereby being concealed at all times and also protected from injury. The device acts automatically to lock the door when the door is swung to closed position, due to the 65 fact that the slot 29, in the flexible element

is swung into a registering position above the latch 19, which is impelled upwardly by the springs 22, mounted beneath the arm 18.

In order to draw and retain the door in a snugly closed position, the handle 12, is rotated from the vertical position shown in Fig. 6, to a horizontal position, thus pulling the slidable plate 16, by means of the connecting rod 14, forwardly in the casing and wedging the latch member against the 75 forward end of the slot 29, in the flexible element. Such movement, of course, is resisted by the compression springs 26, but due to the fact that the eccentric connection of the connecting rod on the cam element 80 causes the cam to be disposed beyond a dead center such as shown in Fig. 3, with the tooth of the cam 11, bearing against the abutment 27, within the casing, the compression of said springs serves to hold the mechanisms in this position until manually released by turning the handle 12.

If for any reason it is desired to fix the door in any open position of adjustment, with the mechanisms controlled by the 90 handle 12, in release position, the head 42, is rotated to move the screw bolt 41, inwardly, causing the clamping foot 44, to bear with pressure against the flexible element 28, holding the same frictionally from 95 slidable movement within the casing and thus retaining the door in the position of adjustment desired. The interfitting telescoping members 31 and 34, serve to protect and conceal the flexible strap member 28, 100 and due to the manner in which the strap is connected to the member 34, by means of the threaded plug 33, a feature of adjustment is obtained which permits the tension on the strap to be changed to suit conditions and take up for wear of the parts. Said telescoping members also limit the opening movement of the door, thereby protecting the hinges from injury and also permitting the use of a cheaper hinge than 110 would otherwise be necessary.

I am aware that various details of construction may be varied through a wide range without departing from the principles of this invention, and I therefore do not purpose limiting the patent granted otherwise than necessitated by the prior art.

I claim as my invention:

1. In a door lock of the class described a casing, a flexible element slidably mounted 120 therein, means adapted to positively engage said flexible element to prevent movement through said casing, eccentrically operated mechanism for actuating said means and an independent mechanism for engaging the 125 flexible element to the casing.

2. In a device of the class described the combination with a door and its frame, of a casing secured on one thereof, a flexible element slidably mounted within said casing 130

and connected to the other thereof, and a plurality of independently operated locking devices associated with said casing to coact with said flexible element to hold the door 5 in any open position and in tightly closed position.

3. In a device of the class described the combination with a door and its frame, of a casing secured upon the door, a flexible element 10 slidable through said casing, means connecting said flexible element with said frame, locking devices associated with said casing for coaction with said flexible element to interlock the same within said casing to 15 prevent movement of the door, said locking devices comprising means clamping said element within the casing and means independently thereof for positively engaging with the element to tension the same and hold the 20 door tightly closed in the frame.

4. In a device of the class described the combination with a door and its frame, of a casing mounted upon the door, telescoping elements connected to the frame and to said 25 casing, a flexible element slidable within said casing and extending within said telescoping elements and positively connected to one thereof, locking devices associated with said casing, one adapted to clamp said flexible element within its casing to resist movement of the door and the other to positively 30 interlock therewith to lock the door in closed position.

5. In a device of the class described the combination with a door and its frame, of a casing mounted upon the door, telescoping elements connected to said casing and to the frame, a slidable element mounted within 35 the casing and positively connected to one of said telescoping elements, spring impelled latching means mounted within said casing for coaction with said flexible slidable element to interlock the same in said casing and prevent movement of the door, and 40 means wedgingly engaging the latching means tightly with said flexible element to draw the door snugly within its frame.

6. In a device of the class described the combination with a door and its frame, of a casing mounted upon the door, a flexible element 45 slidable in the casing, means connecting the same in the door frame, independently operated locking devices in said casing for engagement and coaction with said flexible element to hold the door in an open or closed position, eccentrically operated means for actuating certain of said devices, and mechanism operating to retain said actuating means in a locked position to 55 retain the door snugly closed in its frame.

7. In a device of the class described the combination with a movable element hingedly mounted in a frame, of a casing secured upon said element, telescoping tubes, 60 flexible means extending into the casing at

its free end and extending into and secured to one of said tubes, and mechanism within the casing co-acting with said flexible means to lock the same within the casing.

8. In a device of the class described the combination with a door and its frame, of means pivoted on the frame and having sliding engagement with the door, an automatically acting latching device on said door for co-action with said means to engage therewith to prevent opening of the door beyond a certain position, manually operable means for said mechanisms to force the same closely into engagement with said means to tension the same and draw the 75 door tightly closed and an independently actuated member for locking the door in any open position.

9. In a device of the class described the combination with a door and its frame, of an element pivoted on the frame and having sliding engagement with the door, a slidably mounted spring impelled automatically acting latch mounted on the door for co-action with said element, means manually actuating said latch to draw the same 85 into close engagement with said element to tension said element and draw the door tightly closed and means independent of said latch adapted to co-act with the pivoted 90 element to lock the door in any open position.

10. In a device of the class described the combination with a door and its frame, of telescoping tubes pivotally secured to the frame, means secured to one tube and slidably in the other and having sliding engagement with the door, spring impelled automatically acting latching mechanism mounted on the door adapted to interlock 100 with said means to limit the opening movement of the door, and eccentrically operated means for manually operating said mechanism to tension and maintain tension upon said first mentioned means to draw and 105 hold the door tightly closed in the frame.

11. In a device of the class described the combination with a door and its frame, of a locking device comprising means mounted on the frame and having sliding engagement with the door, automatically acting locking mechanism adapted to engage said means and adapted to be manually operated to tension said means to draw the door tightly closed, and an independently operated auxiliary locking device for co-action with said means to hold the same immovable with respect to said door to maintain the door in any desired open position.

12. In a device of the class described the combination with a door and its frame, of telescoping tubes mounted on the frame, means rigidly secured to one tube having sliding engagement with the door, and automatically acting latching mechanism 125 130

adapted to engage said means to limit the opening movement thereof and adapted for manual actuation to tension said means and draw the door tightly closed in the frame.

5 13. A door lock comprising telescoping tubular members, a flexible member rigidly secured at one end to one of said tubular members, a casing slotted to receive the flexible member therein, means for engaging the flexible member to hold the door closed, and means in the casing for gripping the flexible member at any point to hold the door in any open position.

10 14. In a device of the class described, a flexible slotted member, a spring pressed latch for engaging in said slot, tension members in said casing, and a manually actuated eccentric adapted to co-act with said tension members adapted when the eccen-

tric is adjusted above a dead center to draw 20 said spring pressed latch firmly into the slot against the flexible member.

15. In a door locking device, a casing, a slotted member slidable therein, a latch pivoted to engage in said slot, co-acting 25 members for forcing the latch in the slot to engage the slotted member and exert longitudinal tension thereon, and a manually operated means for exerting transverse tension on the slotted member in any open position of the door. 30

In testimony whereof I have hereunto subscribed my name in the presence of two subscribing witnesses.

BAYARD E. TAYLOR.
